UNITED STATES PATENT OFFICE

99,851

DESIGN FOR LACE

Stephen N. M. Biddle, New York, N. Y.

Application May 8, 1936, Serial No. 62,534

Term of patent 3½ years

To all whom it may concern:

Be it known that I, Stephen N. M. Biddle, a citizen of the United States of America, residing in Manhattan, county of New York and State of New York, have invented a new, original, and ornamental Design for Lace, of which the following is a specification, reference being had to the accompanying drawing, forming part thereof, wherein,

The figure is a plan view of a piece of lace showing my new design.

I claim:

The ornamental design for lace, substantially as shown.

STEPHEN N. M. BIDDLE.
